UNITED STATES PATENT OFFICE.

WILLIAM H. VOSS, OF DAVENPORT, IOWA.

GEARING FOR WASHING-MACHINES.

No. 918,934.

Specification of Letters Patent. Patented April 20, 1909.

Application filed December 13, 1906. Serial No. 347,665.

To all whom it may concern.

Be it known that I, WILLIAM H. VOSS, a citizen of the United States, and a resident of Davenport, in the county of Scott and State 5 of Iowa, have invented certain new and useful Improvements in Gearing for Washing-Machines, of which the following is a clear, full, and exact description.

My invention relates more particularly to 10 mechanical movements for lever washing machines and its object is to regulate the throw of the lever and utilize the momentum of a fly-wheel in connection therewith to assist in the operation of the machine.

Another object is to locate and connect 15 the fly-wheel in such manner that it will, together with its connected gears, be wholly within the bounds of the periphery of the bottom of the tub, and when thus constructed 20 the entire mechanism will be capable of being assembled in a knock-down shape. This I accomplish by the means hereinafter fully described and as particularly pointed out in the claims.

In the drawings:—Figure 1 is a vertical 25 transverse section through a washing machine, showing my improvements applied thereto. Fig. 2 is a detail view of the top gear or reversing mechanism drawn to a larger scale. Fig. 3 is a detail view on an enlarged scale of the lower gearing and connected fly-wheel. Figs. 4 and 5 are fragmental details showing certain portions of the device to be hereinafter more specifically 30 described. Fig. 6 is an enlarged detail section taken on line 6—6, Fig. 1.

Referring to the drawings A represents a suitable tub such as used in washing machines that is preferably provided with a 40 hinged cover B and is supported at a proper elevation above the floor by a suitable number of equi-distant legs a, a, which latter are braced by suitable cross-pieces a', a'. Journaled in bearings c in the center of the cover 45 is a rotary reciprocal stirrer-shaft C that is provided at its lower end with a stirrer-head or dasher C' of any well-known construction. The portion of this stirrer-shaft C extending above its bearings is squared and passes 50 through a rectangular opening in a beveled pinion D with which said shaft is adapted to revolve but at the same time has a longitudinal movement independent of said pinion. Above the pinion D the stirrer-shaft extends 55 through a suitable sleeve E placed be-

tween said pinion and the overhanging arm of a supporting frame F through which said shaft extends and terminates in a head at its upper end.

The upright member of the supporting-frame F is provided with a horizontal bearing f for a short shaft G that carries upon its inner end a combination bevel and spur gear, the diameter of the bevel-gear H of which being greater than that of the spur-gear L, 65 and engages the pinion D. The spur-gear I is placed between the bevel-gear H and the bearing f and engages a longitudinally elongated reciprocal rack J. This rack J is of such length that its opposite end extends 70 beyond the circumference of the top of the tub and is pivotally connected to a vertical lever as will hereinafter more fully appear. The end of the side of this rack J is provided 75 with a longitudinal rib j, and the rack is held in engagement with the spur-gear by the block K the top of which is provided with a groove in which said rib moves and thus effectually prevents the accidental disengagement of the rack and spur-gear while 80 permitting a slight rocking motion of the rack as it moves back and forth on said block. By providing the underside of the outer end of the rack with an inverted open bearing k and causing this open bearing to catch over 85 and engage a pin k' extending transversely through a lever L and a slot therein through which the end of the rack extends, substantially as shown, said rack can be easily removed from said lever. 90

The operating lever L is fulcrumed between the arms of a bracket l located and secured to the side of the tub. The upper or longer branch of this lever extends above the point where the rack J is connected 95 thereto, and terminates in a socket l' in which the shank of a handle L' may be removably or fixedly secured, according as desired. The lower branch of said lever extends a suitable distance below its bearing bracket to a point below the plane of the bottom of the tub, and said portion is preferably bent at an angle to the upper member, substantially as shown in Fig. 1 of the drawings. The free end of this lower branch is provided 100 with a downwardly projecting extension m upon which is mounted a swivel joint M comprising a sleeve journaled on the extension m and prevented from falling off the same by a cotter-pin m', which sleeve is provided with 105 110

two lugs projecting downward therefrom and between which the adjacent end of a horizontally disposed pitman N is pivoted by means of a pin N'. This pitman extends 5 under the tub A and has its opposite end pivoted between the lugs n of a wrist-pin o, which latter is preferably slightly tapered and is journaled in suitable bearings in a boss constituting part of one of the arms of a 10 horizontally disposed gear O, by means of which the rocking movement of the lever L is converted into a rotary motion. Gear O is journaled in bearings in a substantially T-shaped supporting-plate P, preferably at 15 the junction of its members. The ends of the segmentally shaped arms of this supporting-plate are secured to the cross-pieces a' connecting the legs of the tub, and the end of the straight members extends past the 20 point of intersection of said cross-pieces and is provided with a vertical bearing p that extends centrally down through the intersecting point of the cross-pieces and has journaled therein a vertical spindle q. The 25 end of this spindle above said bearing has a pinion Q mounted thereon, and the end thereof below said bearing has a horizontally disposed fly-wheel R. The pinion Q is engaged and driven by gear O and, as its diameter is considerably less than that of said gear, it revolves much faster than the same and the revolution imparted thereby to the fly-wheel R is such that the momentum of 30 the latter, when once under way, materially assists in actuating the lever L and thereby reduces to a minimum the manual effort exerted on said lever to operate the stirrer-shaft and head in the tub through the medium of the mechanism hereinbefore described. 35

By the construction hereinbefore described the machine and its parts can be completely knocked down for the purpose of shipment. By removing the pins from the brackets l, 45 the swivel joint M and the wrist-pin o, the operating lever L, the pitman N and the rack J can be removed from the outside of the tub and placed within the same in a compact manner. By locating the fly-wheel and its 50 operating gears below the bottom of the tub and in a horizontal plane therewith, the same will be entirely out of the way of the operator and not interfere with any movements adjacent to the tub.

55 What I claim as new is:—

1. In mechanism for driving a washing machine, the combination with a rotary reciprocal shaft, a horizontally disposed gear mounted on said shaft, a vertically disposed 60 gear engaging said horizontal gear, a reciprocal rack engaging said vertical gear, and a reciprocal lever removably connected to one end of said rack, of a horizontally disposed fly-wheel journaled below said shaft, and a 65 pitman connected at its outer end by a uni-

versal joint to the lower end of said lever and at its inner end indirectly operating said fly-wheel.

2. In mechanism for driving a washing machine, the combination with a rotary reciprocal shaft, and a reciprocal lever operatively connected to said shaft, of a horizontally disposed fly-wheel, a shaft therefor journaled below and in alinement with the axis of said rotary reciprocal shaft, a pinion 70 on the end of said shaft opposite said fly-wheel, a gear meshing with said pinion, and a pitman one end of which is connected to said reciprocal lever and the other end is secured to said gear.

3. In mechanism for driving a washing machine, the combination with a rotary reciprocal shaft, a gear mounted on said shaft, a reciprocal rack engaging said gear, and a reciprocal lever connected to one end of said 80 rack, of a horizontally disposed fly-wheel, a shaft therefor journaled below and in alinement with the axis of said rotary reciprocal shaft, horizontally disposed speed-increasing gears operating said fly-wheel, and a pitman 85 connecting one of said gears to the lower end of said reciprocal lever.

4. In mechanism for driving a washing machine, the combination, with a shaft, of a pivoted operating lever, driving devices for 95 oscillating the said shaft from one end portion of the said lever, a fly-wheel mounted to revolve in a horizontal plane below the said shaft, a toothed pinion secured to the said fly-wheel, a toothed wheel also mounted to revolve in a horizontal plane and provided with a crank-pin and gearing into the said pinion, and a connecting-rod provided with universal joints and arranged between said crank-pin and the other end portion of the 100 said lever.

5. In mechanism for driving a washing machine, the combination with a shaft, and a toothed pinion for oscillating the said shaft, of a pivoted operating lever working in a 110 substantially vertical plane, a toothed rack operatively connected with the upper end portion of the said lever and gearing into the said pinion, a fly-wheel mounted to revolve in a horizontal plane below the said pinion and rack, a toothed pinion secured to the said fly-wheel, a toothed wheel also mounted to revolve in a horizontal plane and provided with a crank-pin and gearing into the last 115 said pinion, and a connecting-rod provided with universal joints and arranged between the said crank-pin and the lower end portion of the said lever.

6. In mechanism for driving a washing machine the combination with suitable supporting means, legs below the same, cross-braces, a rotary reciprocal shaft journaled in the top of said supporting means, and a reciprocal lever fulcrumed to the side of said supporting means and operatively connected 120 to the said shaft.

to said shaft, of a horizontally disposed fly-wheel journaled below and independent of said supporting means, and reciprocal means through the medium of which motion is transmitted from the lower end of said reciprocal lever to said fly-wheel.

7. In mechanism for driving a washing machine the combination with suitable supporting means, legs below the same, cross-braces connecting said legs, a bearing-plate mounted at the intersection of said braces, a rotary reciprocal shaft journaled in the top of said supporting means, and a reciprocal lever fulcrumed to the side of said supporting means and operatively connected to said shaft, of a horizontally disposed fly-wheel journaled in said bearing-plate below and independent of the supporting means, and reciprocal means through the medium of which motion is transmitted from the lower end of said reciprocal lever to said fly-wheel.

8. In mechanism for driving a washing machine the combination with suitable supporting means, legs below the same, cross-braces connecting said legs, a T-shaped bearing plate mounted at the intersection of said braces, a rotary reciprocal shaft journaled in the top of said supporting means, and a reciprocal lever fulcrumed to the side of said supporting means and operatively connected to said shaft, of a horizontally disposed fly-wheel journaled in said bearing plate below and independent of the supporting means, and reciprocal means through the medium of which motion is transmitted from the lower end of said reciprocal lever to said fly-wheel.

9. In mechanism for driving a washing machine the combination with suitable supporting means, legs below the same, cross-braces connecting said legs, a T-shaped bear-

ing-plate having the ends of its segmental arms secured to said cross-braces and its straight arm connected to the intersection of said braces, a rotary reciprocal shaft journaled in the top of said supporting means, and a reciprocal lever fulcrumed to the side of said supporting means and operatively connected to said shaft, of a horizontally disposed fly-wheel journaled in said bearing-plate below and independent of the supporting means, and reciprocal means through the medium of which motion is transmitted from the lower end of said reciprocal lever to said fly-wheel.

10. In mechanism for driving a washing machine the combination with suitable supporting means, legs below the same, cross-braces connecting said legs, a T-shaped bearing-plate the ends of the segmental arms of which are secured to said cross-braces and its straight arm provided with a vertical bearing at its end that extends through and is secured to said braces at their point of intersection, a rotary reciprocal lever fulcrumed to the side of said supporting means operatively connected to said shaft, of a horizontally disposed fly-wheel the spindle of which is journaled in said vertical bearing below and independent of the supporting means, and reciprocal means through the medium of which motion is transmitted from the lower end of said reciprocal lever to said fly-wheel.

In testimony whereof I have hereunto set my hand and seal this 8th day of December, 1906.
